UNITED STATES PATENT OFFICE.

CHARLES B. CONNELLY, OF SCOTIA, NEW YORK.

CHEMICAL FIRE-EXTINGUISHING APPARATUS.

1,280,168.

Specification of Letters Patent.

Patented Oct. 1, 1918.

Application filed April 8, 1916. Serial No. 89,961.

To all whom it may concern:

Be it known that I, CHARLES B. CONNELLY, a citizen of the United States, residing at Scotia, county of Schenectady, State of New York, have invented certain new and useful Improvements in Chemical Fire-Extinguishing Apparatus, of which the following is a specification.

My invention relates to chemical fire extinguishing apparatus and has for its object the provision of means whereby the production of fire extinguishing fluid is rendered continuous and readily controllable. In chemical fire extinguishing apparatus as heretofore constructed, it is customary to have a definite amount of acid which is emptied into a mixing chamber containing the chemical compound which reacts with the acid to form the extinguishing fluid. Frequently there is no demand for all of the fluid so formed and it is therefore necessary to waste a large part of the materials since the mixing chamber must be cleaned out each time it is used. One of the objects of my invention is to overcome this objection and produce only the amount of fluid desired without wasting any substantial amount of materials.

In carrying out my invention, I provide a relatively large supply of both the acid and chemical compound and control the discharge of these materials into the mixing chamber so that the fluid will be produced only as it is used and when the use of the fluid ceases the supply of the acid and compound is automatically cut off and the production of fluid stopped. I preferably have the container for the materials in duplicate so that one container may be replenished while the other is in use. In this way the production of fluid goes on continually as long as necessary or desired. In one form of my invention, the supply of fluid to the mixing chamber is controlled by the pressure in the chamber so that as soon as a definite pressure is reached in the mixing chamber, the supply ceases and immediately starts again when the pressure falls. A pump, which may be electrically operated, forces the chemical solution into the mixing chamber, and when the supply is shut off by reason of the pressure attaining a predetermined maximum, a by-pass is automatically opened around the pump so that the latter may continue to operate without doing any work until the pressure drops, whereupon

the by-pass is closed and the pump takes up the load once more. I also provide means whereby water under pressure takes up the extinguishing gas when desired. Other objects and purposes of my invention will appear in the course of the following specification in which I have described my invention embodied in concrete form for purposes of illustration.

In the accompanying drawing illustrating one form of my invention, Figure 1 is a diagrammatic view of my improved apparatus; Fig. 2 is a plan view of the same partly in section; Fig. 3 is a detail of one of the pressure governors; and Fig. 4 is a view of my apparatus located upon an automobile.

Referring to the drawing, 10 and 11 represent two tanks for holding the chemical fluid which would ordinarily be solution of bicarbonate of soda in water. These tanks are arranged in duplicate so that one will be filled while the other is in use. 12 is the mixing chamber which will have its interior protected by a lead lining in the usual way. 13 and 14 are lead lined acid chambers which are also in duplicate for the purpose of refilling while the apparatus is in operation. As shown the two acid chambers are attached to the mixing chamber and the latter is on trunnions so that by turning it through an angle of 90° one or the other of the acid chambers will be set into action. As shown in Fig. 1 the acid chamber 13 is in a vertical position so that the acid therein will flow into the mixing chamber. Connection is made from the tanks 10 and 11 in parallel to the mixing chamber through a pipe 15 so that the chemical fluid may pass from either one of the chemical tanks into the mixing chamber, the valves 17, 18, 19 and 20 being supplied for cutting off the tank which is not in use. Pipe 16 carries the water from the source of supply to the tanks.

The chemical fluid is forced from the tanks into the mixing chamber by a pump 21 which may be of any standard design, preferably electrically operated.

In order to control the generation of gas, I provide a valve between each acid chamber and the mixing chamber and a similar valve between the chemical tanks and the mixing chamber. These valves are controlled by the pressure in the mixing chamber so that when the pressure reaches a predetermined maximum, the supply of acid and chemical fluid is cut off. The valve 22

which controls the passage from the acid chamber to the mixing chamber may be of any suitable type. As shown it comprises a valve plug 22 which engages a valve seat 23 to close the passage. This valve is carried by a lever 24 pivoted at 25. The valve is pivoted to the lever intermediate its ends and the free end is connected to a diaphragm 26 which operates to close the valve 22 when the pressure in the chamber reaches a predetermined point, say for instance one hundred pounds per square inch. When the pressure falls below this point, a spring 27 opens the valve in a manner well understood in the art. Valve 28 controlling the passage from the tanks to the mixing chamber is similar in construction to valve 22 but is provided with an additional valve plug 29 controlling a by-pass around the pump 21. When the pressure is below the predetermined point at which the valves are set to close, the valve being open, the chemical fluid will be pumped from the pipe 15 through the valve 30, and pipe 31 to the mixing chamber. When the pressure valve closes the by-pass will be opened around the pump at valve plug 29 so that the pump may continue to operate without load. The passages for the acid and chemical fluid are so proportioned with reference to each other that a complete chemical reaction ensues in the mixing chamber. A pressure gage 32 indicates the pressure in the chamber when the pump is pumping fluid into the chamber. The water supply is connected to pipe 33 and a valve 34 is supplied for controlling the admission of water direct to the mixing chamber as hereinafter described.

A detail of the pressure valve is shown in Fig. 3. This shows a hand wheel 35 for adjusting the diaphragm through stem 36 and a second hand wheel for adjusting the spring. The discharge of the gas from the mixing chamber is through pipe 37 which may be provided with connections for more than one hose 38. The chemical tanks are each provided with an opening 39 having a cover 40 for filling and a similar opening 41 and cover 42 are provided in the acid chamber.

As thus constructed and arranged, the operation is as follows: The tanks 10 and 11 being supplied with a suitable charge of chemical material which will ordinarily be bicarbonate of soda, the valves 18 and 20 will be opened to supply water to these tanks to make a proper solution. The acid chambers 13 and 14 being also filled with acid, ordinarily sulfuric acid, the valve 30 will be opened and the pump 21 started. There being no pressure at starting in the mixing chamber, the valve 28 is in open position, that is, in position to admit fluid through the pipe 31 and valve 22 is likewise open to admit acid into the mixing

chamber. The pump will now pump chemical fluid into the mixing chamber and by reason of the acid admitted from the acid chamber, gas will be rapidly generated which may be discharged through the hose 70 in a manner well understood. When the pressure in the mixing chamber rises to, say for instance, one hundred pounds per square inch, both of the pressure valves close, thereby cutting off the acid and also the chemical fluid. The closing of the valve 28 opens the bypass around the pump so that the pump may continue to operate without load. When the pressure falls due to the gas being consumed, the valves will again open 80 and supply the acid and chemical fluid as before. These valves will continue to open and close as the pressure rises and falls although the pressure will never vary to any considerable extent. When the supply 85 of chemical fluid in one tank is exhausted, the valves controlling it may be closed and the supply renewed. In the meantime the other tank will be utilized. The same is true of the acid chambers, it only being necessary to turn the acid chamber on its axis to bring the full chamber into action and place the empty one in position to be filled. When the operation is stopped, there will be substantially no material in the chemical 95 chamber and there will therefore be no waste.

It will be noted that I provide means whereby the water supply may be charged with gas for fire extinguishing purposes. 100 In order to do this, it is only necessary to adjust the pressure valves so that the pressure as indicated at the gage will be substantially equal to the water pressure. The water from the supply pipe may therefore 105 enter the mixing chamber by the opening of valve 34 and be discharged through the hose just as the gas is discharged.

It will be seen that I have supplied means whereby the generation of gas will go on 110 continuously and indefinitely and when the operation is over, there are no materials to be wasted. The supply of material may be replenished without interfering with the operation of the apparatus and the pump need 115 never be stopped when the apparatus is in use.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from 125 the spirit of my invention, the scope of which is set forth in the annexed claims.

What I claim as new, and desire to secure by Letters Patent of the United States, is:

1. A chemical fire extinguishing apparatus 130

comprising a mixing chamber, an acid chamber arranged to feed acid to the mixing chamber, a tank for the chemical fluid, means for delivering the fluid into the mixing chamber and means for automatically controlling the discharge of acid and fluid to the mixing chamber in accordance with the pressure in said chamber.

2. A chemical fire extinguishing apparatus comprising a mixing chamber, an acid chamber arranged to feed acid to the mixing chamber, a tank for the chemical fluid, a pump arranged to force the fluid into the mixing chamber to generate gas and means for automatically controlling the generation of gas in accordance with the pressure in the mixing chamber.

3. A chemical fire extinguishing apparatus comprising a mixing chamber, an acid chamber arranged to feed acid to the mixing chamber, a plurality of tanks for the chemical fluid, means for delivering fluid from either of said tanks to the mixing chamber while the other is in condition to be charged, and means controlled by the pressure in the mixing chamber for controlling the discharge of acid and fluid to the mixing chamber.

4. A chemical fire extinguishing apparatus comprising a mixing chamber, an acid chamber arranged to feed acid to the mixing chamber, a tank for the chemical fluid, a pump for forcing the chemical fluid into the mixing chamber to generate gas, a bypass around the pump, and means whereby the bypass is opened when the pressure in the mixing chamber reaches a predetermined value.

5. A chemical fire extinguishing apparatus

comprising a mixing chamber, an acid chamber arranged to feed acid to the mixing chamber, a tank for the chemical fluid, a pump for forcing the chemical fluid into the mixing chamber to generate gas, a bypass around the pump, and means whereby the bypass is opened and the discharge of acid and fluid to the mixing chamber is cut off when the pressure in the mixing chamber reaches a predetermined value.

6. A chemical fire extinguishing apparatus comprising a mixing chamber, an acid chamber arranged to feed acid to the mixing chamber, a tank for the chemical fluid, a source of supply of water connected to said tank, means for delivering chemical fluid into the mixing chamber, means for automatically controlling the discharge of acid and fluid to the mixing chamber in accordance with the pressure in said chamber, and means for admitting water from the source of supply direct to the mixing chamber.

7. A chemical fire extinguishing apparatus comprising a mixing chamber for generating fire extinguishing gas under pressure, a water supply under pressure connected thereto, and means whereby the pressure in the chamber can be made equal to the water pressure so that the water will be charged with the gas in the chamber.

8. A chemical fire extinguishing apparatus comprising a rotatable mixing chamber, two acid chambers at right angles to each other mounted thereon so that when one is in vertical position for use, the other will be in a horizontal position for charging.

In witness whereof, I have hereunto set my hand this 6th day of April 1916.

CHARLES B. CONNELLY.
